MINING AND LOADING MACHINE

Joseph J. Slomer, Chicago, Ill., assignor to Goodman Manufacturing Company, Chicago, Ill., a corporation of Illinois

Application June 12, 1951, Serial No. 231,070

6 Claims. (Cl. 198—109)

1

This invention relates generally to mining and particularly to an improved mining and loading machine of the type sometimes referred to as a continuous mining machine for removing coal, salt, ore and the like directly from the solid.

This type of machine is illustrated in detail in Frank A. Lindgren and Richard C. Lundquist application Serial No. 186,326, filed September 23, 1950. Briefly, it comprises a portable main frame with horizontally swingable front and rear auxiliary frames over which is trained an endless chain-type conveyor. At the front of the conveyor is gathering means effective to pick up material from the floor and transfer it to the conveyor. In operation, the cutting and dislodging head, also carried by the auxiliary frame, is dumped into the mine face as the auxiliary frame, which is reciprocable relative to the main frame, moves forward. A loop is formed in a slack portion of the conveyor chain and a pressure-actuated cylinder or hydraulic motor is provided for maintaining the loop extended to keep it properly tensioned during forward and rearward reciprocations of the auxiliary frame. This automatically varies the effective length of the conveyor chain when the auxiliary frame reciprocates and also varies it in a lesser extent when either of the auxiliary frames is swung or tilted.

In the above-mentioned co-pending application, a hydraulic control system was provided which utilized separate pumps, one exclusively for the chain tensioning circuit, and another for the swinging, tilting and dumping functions of the auxiliary frames. In service, this arrangement has been found disadvantageous since the failure of either pump would necessitate complete shutdown of the machine.

Accordingly, a specific object of the present invention is to provide an improved hydraulic control system in a continuous miner of the type mentioned which will be more rugged in use and which may function even after failure of one of the pump units.

Other objects and advantages will be apparent from the following description taken in connection with the drawings in which:

Figure 1 is a plan view, partly cut away to show certain components, of a continuous mining machine employing one embodiment of the present invention; and

Fig. 2 is a fragmentary, diagrammatic side view of the machine having superimposed on it a hydraulic control system according to the present invention.

Referring now more particularly to the draw-

2

ings, the mining machine is substantially identical to that described in the above-mentioned patent application, Serial No. 186,326 except for the details of the particular improvement described herein. For details of the machine generally, reference should be made to the earlier application.

Briefly, the miner shown in the present drawings comprises a main frame 21, portably mounted on endless treads 22 and driven by motors 23 through gearing not shown. A rear auxiliary frame or boom 24 is mounted for sidewise swinging movement about a vertical axis W and for up and down tilting movement about a horizontal axis Y. Cylinder and piston means 26 and 27, 28, acting between the main and rear auxiliary frames, serve respectively to swing and tilt the rear auxiliary frame.

At the front of the main frame, a sub-frame 28 is swingable about a vertical axis X by cylinder and piston means 29 attached to the main frame.

An auxiliary frame 31 is reciprocably mounted on the swingable sub-frame, being movable by piston and cylinder means 32, 32 acting between the sub-frame and the auxiliary frame. The auxiliary frame 31 carries a cutting and dislodging head 25, and a pair of side-raking gathering elements 33, 33, all of which are driven (by means not shown) from motors 34, 34. The gathering elements 33 are both mounted atop a gathering apron 36 which is pivotally mounted as at 37 at a pair of transversely spaced points on the reciprocable frame. A flexible, endless conveyor member, in this case a center strand conveyor chain 38, is trained about direction-changing roller elements 39 and 41 carried respectively by the rear and front auxiliary frame members 24 and 31. The gathering element 33 and apron 36 provide a convenient forward mounting position for the direction-changing element 41 so the material picked up by the gathering mechanism from the floor may be conveniently transferred to the conveyor for discharge from the rear end thereof.

It will be apparent that as the reciprocable frame moves forwardly, the conveyor must extend. This extension is accommodated by the telescopically assembled chain-supporting sections 42 and 43 carried by the swingable sub-frame 28 and the auxiliary frame 31 respectively.

To tension the conveyor chain, it is formed into a double bend loop, on the slack side, as defined by driving sprocket 44, spreadable idlers 45 and 46, and idler 47. The idlers 45, 46 are urged apart to expand the loop whenever pressure is

introduced in the fluid operable motor means 48, which is here shown as a cylinder and piston acting between the spreadable idlers 45 and 46.

Referring now to the improved hydraulic control system, a pair of pumps 51 and 52 are arranged in parallel with one another and adapted to draw fluid from a tank 53 through conduits 54, 56 and 57. Since they are arranged in parallel the pump units 51 and 52 normally cooperate to feed pressure into a common output conduit 58 when they are both operating. For convenience, the two pump units may be referred to collectively as the pump means 59. The output side of the pump is connected by conduit 58 to a manually operable distributing or control valve 61 which controls various swinging, tilting, and sumping functions of the machine.

The distributing valve 61 is here shown as a conventional multi-port valve of the type described in detail in co-pending application, Serial No. 202,503, of Joseph J. Slomer, filed December 23, 1950. Briefly, the multi-port distributing valve comprises a series of individual connected units 61a, 61b, 61c, and 61d stacked in side by side relationship, in communication with each other, and each controlling a single function. They are so interconnected, that when the handles 62 are all in their neutral position (as shown in solid lines) fluid is by-passed directly to tank through the conduit 63.

Describing the valve unit 61a, for example, it has inlet-outlet ports A—A' connected respectively to correspondingly designated ports at the ends of the sumping cylinders 32. Thus, when the operating handle 62 of valve unit 61a is moved inwardly to its inner broken line position, fluid flows out of the valve port A, into sumping cylinders 32 and displaces fluid back through valve port A' (which now communicates, within the valve assembly, with the return conduit 63) to tank. And, when the operating handle is moved outwardly, to its outer broken line position, fluid is reversed through ports A—A' to cause the sumping cylinder to be actuated in the opposite direction, with the displaced fluid being returned to tank through the port A.

In a similar fashion the front swing cylinder 29, the rear swing cylinders 26, and rear lift cylinders 21 are actuated by valve blocks 61b, 61c, and 61d, respectively. This valve block arrangement may be added to, as indicated at 64, for actuating an additional function or functions.

It is essential that the motor 66, which turns the conveyor driving sprocket 44, never be started before the chain is properly tensioned. Otherwise the chain would slip off the rotating sprocket and damage would result. To this end, a pressure switch 67 is connected into the pump output conduit 58 and controls the motor lines 68, 69 to permit starting by main switch 71 only when the pump units are producing enough pressure to properly tension the chain in the manner to be described.

A by-pass conduit 72, having a pressure regulating valve 73 and a check valve 74 in series, is connected between the tensioning cylinder 48 and the pump output line 58. Usually, the normal back-pressure in the output line will be high enough to direct sufficient pressure up the line 72 to actuate the tensioning cylinder. If not, a metering or throttle-type back-pressure valve, indicated in broken lines at 76, may be employed in the pump output line. To obtain the maximum possible benefit from the normal back-pressure in the output line, the by-pass line 72

should be connected as close as possible to the pump means 59.

A pressure relief valve 77, set at a pressure higher than the output pressure of the regulating valve 73, is provided in a return line 78 which connects the tensioning cylinder and the tank.

In operation, as pressure is fed into the rear ends of the sumping cylinders 32 to advance the reciprocable frame 31 during sumping, the effective length of the conveyor 39 will be extended as the direction-changing element 41 is pulled forward away from the relatively fixed element 39. As this movement proceeds the loop in the slack side of the chain will be decreased thereby forcing fluid out of the tensioning cylinder 48 into the line 72. Now, since it cannot pass through the check valve 74 it will be diverted through the pressure relief valve 77 and returned to tank through the conduit 78.

In an application where the sumping cylinders 32 and the swinging and tilting cylinders are sized to require an operating pressure of one thousand pounds per square inch under normal operating conditions, pumps 51 and 52 should be rated at, say, fifteen hundred pounds per square inch capacity in order to provide a reasonable safety factor. The pumps may be of the same gallon-per-minute capacity if desired, or they may be different, depending on the requirements of the particular installation. If the tensioning cylinders 48 are sized to operate at one hundred pounds per square inch or less, the pressure reducing valve 73 will be set to provide a somewhat higher constant output pressure, say, one hundred and fifty pounds per square inch. And with this setting, the relief valve 77 will be adjusted to relieve at a somewhat higher pressure, say, two hundred pounds per square inch.

With the hydraulic operating and control system herein described, the operation of the machine will not be critically dependent on the constant functioning of any one pump. Thus, while both pumps 51 and 52 may be required for full speed operation of all the parts, either one of the pumps would be capable of automatically taking over operation of the entire machine, at somewhat reduced speed, upon failure of the other pump. In actual practice in a mine, this would be a substantial advantage for it would permit the operators of the machine in many cases to complete a shift or clean up a room while postponing shut-down of the machine for repairs to the next shift.

While one form in which the present invention may be embodied has been shown and described, it will be understood that various modifications and variations thereof may be effective without departing from the spirit and scope of the invention as defined by the appended claims.

60 What I claim is:

1. In a mining and loading machine, the combination of a portable main frame, an auxiliary frame carried by said main frame and mounted for back and forth reciprocable movement and for horizontal swinging movement with respect thereto, an endless conveyor member trained about direction-changing elements carried respectively by said main and auxiliary frames, means for maintaining a predetermined tension in said conveyor member throughout the range of movements of said auxiliary frame including means between said direction-changing elements for training said conveyor member in the shape of a loop and having fluid-operable motor means associated therewith and effective to expand said

loop responsive to fluid under pressure, fluid pressure operable means for adjustably moving said auxiliary frame, main valve means for controlling operation of said fluid pressure operable means, pump means connected to draw fluid from a tank and supply fluid to said main control valve means, conduit means connecting said pump means with said main control valve means for effecting actuation of the individual adjusting functions of the auxiliary frame upon operation of said valve means, a by-pass conduit connecting said motor means with the output side of said pump means on the inlet side of said main control valve means, pressure reducing means in said by-pass conduit for diverting a substantially constant pressure to said motor means to tension said conveyor member, return conduit means connecting said by-pass conduit with said tank and having a fluid relief valve set to relieve fluid pressure and return fluid to said tank at a predetermined pressure above the output setting of said pressure reducing means, and a back pressure unit in said main conduit unit set to create a predetermined back-pressure in said by-pass conduit greater than the output setting of said pressure reducing means.

2. In a mining and loading machine the combination of a portable main frame, an auxiliary frame carried by said main frame and mounted for back and forth reciprocable movement and for horizontal swinging movement with respect thereto, an endless flexible conveyor member trained about direction-changing elements carried respectively by said main and auxiliary frames, means for maintaining a predetermined tension in said endless conveyor member throughout the range of adjusting movements of said auxiliary frame including means between said direction-changing elements for training said member in the shape of a loop and having fluid-operable motor means associated therewith and effective to expand said loop responsive to fluid under pressure, fluid pressure operated motor means for effecting adjustment of said auxiliary frame, main control valve means for controlling operation of said fluid pressure operated means, a source of supply of fluid under pressure including a tank, a pump connected therewith, main conduit means connecting said pump to said main control valve means, a by-pass conduit connected from said main conduit means to said motor means, a back pressure unit in said main conduit on the downstream side of the point of connection of said by-pass conduit thereto, to set up a predetermined back pressure in said by-pass conduit, return conduit means connecting said by-pass conduit with said tank and having a relief valve set to return fluid to said tank at a predetermined pressure above the setting of said back pressure unit.

3. In a mining and loading machine the combination of a portable main frame, an auxiliary frame carried by said main frame and mounted for back and forth reciprocable movement and for horizontal swinging movement with respect thereto, an endless flexible conveyor member trained about direction-changing elements carried respectively by said main and auxiliary frames, means for maintaining a predetermined tension in said endless conveyor member throughout the range of adjusting movements of said auxiliary frame including means between said direction-changing elements for training said member in the shape of a loop and having fluid-operable motor means associated therewith and

effective to expand said loop responsive to fluid under pressure, fluid pressure operable means for adjustably moving said auxiliary frame, valve means controlling operation thereof, a tank, a pump connected with said tank, a main conduit connecting said pump to said valve means, a bypass conduit connected from said main conduit to said fluid motor means, a return conduit connecting said by-pass conduit with said tank, a back pressure unit in said main conduit on the downstream side of the point of connection of said by-pass conduit thereto, for creating a predetermined pressure in said by-pass conduit, a relief valve in said return conduit set to return fluid to said tank at a predetermined pressure above the output setting of said back pressure unit, and a check valve in said by-pass conduit on the downstream side of the point of connection of said return conduit thereto.

4. In a conveyor, an articulated frame having direction-changing devices adjacent the ends thereof, an endless conveyor element extending along said frame and changing its direction about said direction changing devices, a hydraulically actuated device for adjustably moving said frame to its various positions of articulation, means for maintaining a predetermined uniform tension on said conveyor element in all positions of articulation of said frame including a plurality of longitudinally spaced direction-changing devices intermediate said first named direction changing devices, and about which said conveyor element is trained in the form of an open loop, fluid motor means effective to expand said loop, a tank, a pump connected thereto, control valve means for operating said hydraulically actuated devices, a main pressure line connecting said pump with said control valve means, a by-pass pressure line connecting said main pressure line with said fluid motor means, a return line connecting said by-pass pressure line with said tank, a relief valve in said return line, to return fluid to said tank upon predetermined excess pressures, and a back pressure valve unit in said main conduit on the downstream side of the point of connection of said by-pass pressure line thereto, for creating a predetermined back pressure in said by-pass conduit.

5. In an endless conveyor the combination with a main frame, an auxiliary frame mounted thereon for movement with respect thereto, hydraulic actuated means for adjustably moving said auxiliary frame, direction changing devices adjacent the opposite extremities of said frames, an endless flexible conveyor element trained about said direction changing devices, means for maintaining a predetermined tension on said endless conveyor element throughout the range of movement of said auxiliary frame with respect to said main frame including two spaced direction-changing devices disposed between said first mentioned direction-changing devices and training said endless conveyor element in the form of an open loop, fluid-operable motor means associated with said second mentioned direction-changing devices and effective to expand said loop responsive to fluid under pressure, fluid pressure operated means for moving said auxiliary frame with respect to said main frame, a tank, a pump connected with said tank, valve means controlling operation of said fluid pressure operated means, a main pressure line connecting said pump to said valve means, a by-pass pressure line connected between said pressure line and said fluid motor means, a return line connected from said

by-pass pressure line to said tank, a relief valve in said return line set to return fluid to tank at a predetermined pressure, a pressure reducing valve in said by-pass pressure line, and a check valve in said by-pass pressure line at the outlet of said pressure reducing valve and on the upstream side of the point of connection of said return line to said by-pass pressure line.

6. In an endless conveyor, a main frame, an auxiliary frame mounted on said main frame for adjustable movement with respect thereto, direction changing devices adjacent the extremities of said frames, an endless conveyor element trained about said direction changing devices, hydraulic actuated means for adjustably moving said auxiliary frame, means for maintaining a predetermined uniform tension on said conveyor element during relative movement of said auxiliary frame with respect to said main frame including two spaced direction-changing devices 20 between said first mentioned direction changing devices and training said conveyor in the form of an open loop, fluid operated motor means operable to move said direction-changing devices to expand the loop, a tank, control valve means 25 for said hydraulic actuated means, controlling movement of said auxiliary frame, a main pres-

5 10 15

sure line leading to said control valve means, two pumps connected in parallel from said tank to said main pressure line, a by-pass pressure line connected from said main pressure line to said hydraulic motor means, a back pressure valve unit in said main pressure line set to create a predetermined back pressure in said by-pass pressure line regardless of the operative position of said control valve means, a check valve in said by-pass pressure line, a return line connected with said by-pass pressure line on the outlet side of said check valve, and a relief valve in said return line set to return fluid to tank at a predetermined pressure above the output setting of said back pressure valve unit.

JOSEPH J. SLOMER.
